Primary Examiner — Kimberly Barnes(74) *Attorney, Agent, or Firm* — Morgan, Lewis & Bockius LLP(57) **CLAIM**

The ornamental design for a robotic vacuum cleaner, as shown and described.

DESCRIPTION

1. Robotic vacuum cleaner

1.1 : Front

1.2 : Back

1.3 : Left

1.4 : Right

1.5 : Top

1.6 : Bottom

1.7 : Perspective

1 Claim, 7 Drawing Sheets(56)
